CLARENCE EVELYN KING, OF HARPENDEN, ENGLAND, ASSIGNOR TO GENERAL MOTORS CORPORATION, OF DETROIT, MICHIGAN, A CORPORATION OF DELAWARE

SLEEVE-VALVE ENGINE

Application filed August 19, 1927. Serial No. 214,081.

This invention relates to internal combustion engines and more specifically to means for cooling the cylinder heads of such engines.

- It is an object of this invention to provide a more efficient means for cooling internal combustion engines and more specifically to provide a means whereby cooling water is delivered directly from the radiator to the cylinder head of the engine.
- 10 Other objects of the invention will be obvious from the following description of the preferred embodiment of my invention which is illustrated in the accompanying drawings, in which:

- 15 Figure 1 is a somewhat diagrammatic view of the radiator, engine and transmission of an automotive vehicle showing the water connections between the radiator and the engine head.
- 20 Figure 2 is a cross section on the line 2—2 of Figure 1.

- Figure 3 is a view of the cylinder head water jacket, mainly in top plan and partly in section on the line 3—3 of Figure 2.
- 25 In the drawings the reference character 5 indicates the radiator, 6 the engine and 7 the transmission of an automobile.

The engine 6 is of the single sleeve valve type and includes a block 8 having therein 30 a plurality of cylinders which are water jacketed, as indicated at 9, a sleeve valve 10 movable in each cylinder, and a piston 11 movable in each sleeve.

The reference character 12 indicates the 35 cylinder head which is secured to the cylinder block 8 by bolts, such as 20, and which has a depending hollow cylindrical portion 13 extending down into each cylinder. The sleeve 10 slides between the outer wall of the part 40 13 and the inner wall of the cylinder. Inside of and extending upwardly from the lower end of the cylindrical portion 13 is a hollow conical portion 14 which is internally threaded at its upper end for the reception of the 45 spark plug 15. As is clearly shown in Fig-

ure 2, there is a space 16 between the cylindrical portion 13 and the conical portion 14 for cooling water.

The cylinder head cover plate 17 has openings 18 into which the upper ends of the 50 conical portions 14 fit. The outer edges of the cover plate are secured to the cylinder block by bolts such as 19. The joints between the cylinder head and the cylinder block, between the cover plate and the cylinder block, and 55 between the conical portion of the cylinder head and the cover plate are all made waterproof.

As may be seen from the drawing, there are 60 two separated channels in the cover plate, one, 21, for the water entering the water jacket and the other, 22, for the water leaving the water jacket. The cylinder head forms the bottom of the channel 22, but the channel 21 has a 65 lower wall 23 integral with the cover plate. This lower wall 23 has a perforation 24 adjacent each cylinder. Secured to the lower wall 23 beneath each opening 24 is a funnel 25 with its spout projecting into the space 16. Water enters the channel 21 in the cover 70 plate at 26 directly from the pump 32. In order to prevent the water from flowing through the water jacket without passing through the hollow spaces 16 in the depending portions of the cylinder head the channels 21 and 22 are separated by partitions 28 and 28'. Since these partitions prevent the 75 water going directly from the channel 21 to the channel 22, in order to get out of the water jacket, the water must flow, through the openings 24, into the funnels 25, which direct it into the spaces 16 where it cools the depending portions of the cylinder head. From the space 16 the water flows into the channel 22 out of the water jacket at 29 into the pipe 80 30 which returns it to the radiator.

As shown in Figure 1 the cooling water for the cylinder head is drawn directly from the bottom of the radiator 5 through the pipe 31 by the pump 32 which is driven by the fan 85 90

shaft 33. The pump forces the water into the cylinder head water jacket at 26 through which it flows and is returned to the top of the radiator as described above.

5 It is well known that the portions of the cylinder head directly above the pistons are heated more and raised to a higher temperature than any other part of the engine. Since in my cooling system the water for cooling 10 these portions is drawn from the bottom of the radiator, where it is coolest and is pumped directly to the cylinder head water jacket where the funnels 25 direct it into the hollow portions of the cylinder head which depend into the cylinder, my system is very efficient in cooling these portions of the engine. It is to be understood that the cylinder block 15 can be cooled in any ordinary or desired manner.

20 Though my cooling means has been shown and described in connection with the cylinder head of a sleeve valve engine it may be used elsewhere and my invention is limited in scope only by the appended claims.

23 I claim:

1. In an engine having a cylinder and a cylinder head having a hollow portion projecting into the cylinder, a cover plate for the cylinder head having therein a conduit having 20 means to direct cooling fluid directly to the hollow portion.

2. In an engine having a cylinder and a cylinder head having a hollow portion projecting into the cylinder, a cover plate for the cylinder head having therein a conduit having 35 means, including a funnel, to direct cooling fluid directly into said hollow portion, said cover plate also having a channel for conducting the fluid from the hollow portion of the cylinder head, and means to prevent passage 40 of the fluid from the conduit to the channel without passing through the hollow portion.

3. In an engine head cooling system, means to conduct cooling fluid directly to said cylinder head, and means to direct said fluid directly on the portion of said head which is 45 directly above the piston.

4. A cover plate having fluid inlet and discharge channels, said inlet channel having a lower wall having perforations therein at intervals, and means adjacent said perforations to direct cooling fluid to the portion of the cylinder head directly above each cylinder.

5. A cover plate having fluid inlet and discharge channels, said inlet channel having a lower wall having perforations therein at intervals, and a funnel adjacent each perforation to direct cooling fluid to the portion of the cylinder head directly above each cylinder.

6. A cover plate having fluid inlet and discharge channels separated by a partition, said inlet channel having a lower wall having perforations therein at intervals, and a funnel adjacent each perforation to direct cooling

fluid to the portion of the cylinder head directly above each cylinder.

7. In an internal combustion engine having a plurality of cylinders and a jacketed cylinder head, a conduit in said jacket extending longitudinally of the engine and having therein a plurality of openings through each of which cooling fluid is adapted to be discharged onto the portions of said head directly above said cylinders.

8. In an internal combustion engine having a cylinder and a cylinder head having a hollow portion projecting into the cylinder, a cover plate for the cylinder head having therein a conduit having therethrough an opening through which cooling fluid is adapted to be discharged into said hollow portion of the cylinder head, said cover plate also having therein a channel for conducting fluid from the hollow portion of the cylinder head, and means to prevent passage of fluid from the conduit to the channel without passing through the hollow portion.

9. A cylinder head cover plate having inlet and discharge channels for a cooling fluid, 90 said inlet channel having a wall having therethrough a plurality of openings through each of which cooling fluid is adapted to be discharged onto the portion of the cylinder head directly above each cylinder.

10. In an internal combustion engine having a plurality of cylinders, jacketed means for closing the open ends of said cylinders, an inlet conduit in said jacket having therethrough openings through which cooling 100 fluid is adapted to be discharged onto the portions of said first-mentioned means directly above the cylinders, an outlet channel, and means to prevent passage of fluid from the conduit to the channel without passing over the portions of said first-mentioned means directly above the cylinders.

11. In an internal combustion engine having a plurality of cylinders, jacketed means having hollow portions projecting into the cylinders for closing the open ends of the cylinders, a conduit in said jacket having therethrough openings through which water is adapted to be discharged into the hollow portions of said first-mentioned means, an outlet channel, and means to prevent the passage of water from the conduit to the channel without passing through said hollow means.

12. In an engine which includes a cylinder and a cylinder head having a hollow portion projecting into the cylinder, a cover plate for the cylinder head having therein a conduit on which is provided means including a funnel to direct cooling fluid directly into the hollow portion of the cylinder head.

13. In an engine which includes a cylinder and a cylinder head having a hollow portion projecting into the cylinder, a cover plate for the cylinder head having therein a conduit on which are provided means to di-

rect cooling fluid directly to the hollow portion of the head, and a channel for conducting the fluid from the cylinder head.

14. In an engine which includes a cylinder and a cylinder head having a hollow portion projecting into the cylinder, a cover plate for the cylinder head having therein a conduit on which are provided means to direct cooling fluid directly to the hollow portion of the head, a channel for conducting the fluid from the hollow portion of the head, and means to prevent passage of the fluid from the conduit to the channel without passing through the hollow portion.

15. In testimony whereof I affix my signature.
CLARENCE EVELYN KING.
